UNITED STATES PATENT OFFICE

DESIGN FOR A SWEATER

Abraham Gepner, Birmingham, Ala.

Application February 20, 1939, Serial No. 83,114

Term of patent 7 years

To all whom it may concern:

Be it known that I, Abraham Gepner, a citizen of the United States of America, residing at Birmingham, in the county of Jefferson and State of Alabama, have invented a new, original, and ornamental Design for a Sweater, of which the following is a specification, reference being had to the accompanying drawing, forming part thereof.

The figure is a front elevational view of a sweater, showing my new design.

The back of the sweater is substantially the same in appearance as the front.

The characteristic feature of my design resides in the specific combination on the sleeveless sweater disclosed of the relatively wide contrastingly colored stripes at the top and bottom thereof in association with the diamond emblem on the front as shown.

I claim:

The ornamental design for a sweater, as shown and described.

ABRAHAM GEPNER.
